PLLC; Timothy DeWitt

(57) **CLAIM**

The ornamental design for a pneumatic connector, as shown and described.

DESCRIPTION

FIG. 1 is a perspective view of a pneumatic connector showing our new design;

FIG. 2 is a right side view of the pneumatic connector shown in FIG. 1;

FIG. 3 is a left side view of the pneumatic connector shown in FIG. 1;

FIG. 4 is a front view of the pneumatic connector shown in FIG. 1;

FIG. 5 is a back view of the pneumatic connector shown in FIG. 1;

FIG. 6 is a top view of the pneumatic connector shown in FIG. 1; and,

FIG. 7 is a bottom view of the pneumatic connector shown in FIG. 1.

The broken lines in the drawings illustrate portions of the pneumatic connector that form no part of the claimed design.

1 Claim, 4 Drawing Sheets
